CLAIM

The ornamental design for a pet food desiccant with case, as shown and described.

DESCRIPTION

FIG. 1 is an exploded front, bottom perspective view of a pet food desiccant with case, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1; and,

FIG. 10 is another perspective view of the pet food desiccant with case, shown in an assembled configuration.

The dashed broken lines in the figures illustrate portions of the pet food desiccant with case that form no part of the

(Continued)

claimed design. The dash-dot broken lines in FIGS. 1 and 9 represent the designation of enlargement views and form no part of the claimed design.
